CLAIM

The ornamental design for a control enhancing holder
for emery boards, as shown and described.

DESCRIPTION

FIG. 1 is a front elevational view of a control enhancing
holder for emery boards showing my new design, the
rear view being identical in appearance;

FIG. 2 is a top plan view thereof, the bottom view being
identical in appearance; and,

FIG. 3 is a side elevational view thereof; the opposite
side being identical in appearance.

FIG. 1

FIG. 2

FIG. 3
